UNITED STATES PATENT OFFICE.

ORSON W. BRENIZER, OF PHILADELPHIA, PENNSYLVANIA, ASSIGNOR OF ONE-FIFTH
TO ANDREW V. GROUPE, OF PHILADELPHIA, PENNSYLVANIA.

CABLE-SUPPORT.

1,373,164.

Specification of Letters Patent.

Patented Mar. 29, 1921.

Application filed March 19, 1918. Serial No. 223,269.

To all whom it may concern:

Be it known that I, ORSON W. BRENIZER, a citizen of the United States, residing at Philadelphia, in the county of Philadelphia 5 and State of Pennsylvania, have invented certain new and useful Improvements in Cable-Supports, of which the following is a specification.

My invention relates to improvements in cable supports adapted to be hung at intervals upon a supporting or messenger wire and to receive and support a cable.

The object of my invention is to provide a novel, simple and efficient support 15 which may be formed of a single piece of wire and which may be easily and quickly applied to a supporting or messenger wire, and which, when applied thereto, will firmly grip the messenger wire in a manner to prevent displacement of the support when a 20 cable is drawn therethrough and when the support is in service.

With the above and related objects in view, my invented support consists of the 25 elements and the combinations of them hereinafter described and claimed.

In the accompanying drawings, illustrating my invention,

Figure 1 is a face view of a cable support 30 embodying my invention and applied to a messenger wire which is shown in transverse section.

Fig. 2 is a side view of the parts shown in Fig. 1.

Fig. 3 is a top view thereof.

Fig. 4 is a face view of the support in the normal condition thereof, and showing, by dotted lines, the position to which the parts are sprung to receive the messenger 40 wire.

Referring to the drawings, the cable support is preferably formed of a single piece of spring wire and comprises a loop 2 having end portions 3 and 4, hooks 5, 6 and 7, 45 and an arm 8.

The hooks 5 and 7 face different directions and form continuations of the end portions 3 and 4, respectively, and they are adapted to be hooked around the messenger 50 wire 9 from opposite sides thereof. The arm 8 forms a continuation of the hook 5 and the hook 6 forms a continuation of the arm 8 and it extends therefrom on lines following the lines of the hook 5 in spaced 55 relation thereto and it is adapted to be

hooked around the wire 9 with the hook 5. The hook 7 is adapted to be hooked around the messenger wire 9 between the hooks 5 and 6, as clearly illustrated.

When the support is applied to the messenger wire 9, the loop 2 extends transversely beneath the same and is adapted to receive a cable, indicated at 10 in Figs. 1 and 2, the hooks 5 and 6 are hooked around the wire 9 from one side thereof, the hook 65 7 is hooked around the wire 9 from the opposite side thereof and the free end portion of the hook 7 extends between the wire 9 and the arm 8.

The normal condition of the support is 70 shown by full lines in Fig. 4; and, in applying the support to the wire 9, the loop 2 is grasped by hand and the device is moved relatively to the wire 9 to cause it to enter the loop 2. The parts of the device 75 are then sprung into the position shown by dotted lines in Fig. 4. This done, the hooks 5 and 6, as a unit, are hooked around the wire 9 from one side thereof, and the hand pressure against the device, holding 80 it in the condition shown by dotted lines in Fig. 4, is then relieved, permitting the device to return part way to the normal condition shown by full lines in Fig. 4. During this return action of the device, the hook 85 7 is hooked around the wire 9 from the opposite side thereof and the free end portion of the hook 7 enters between the wire 9 and the arm 8 and comes to rest in engagement with or in close proximity to said arm, as 90 clearly shown in Figs. 1, 2 and 3. The engagement of the hooks 5, 6 and 7 with the wire 9 prevents the complete return of the device to the normal condition shown by full lines in Fig. 4; and, thereafter, the tendency of the device to resume said normal condition, causes the hooks 5, 6 and 95 7 to firmly grip the messenger wire 9.

When the support is applied to the wire 9, the free end portion of the hook 7, engaging the arm 8, locks the hooks 5 and 6 upon the wire 9 and prevents the accidental disengagement of the device therefrom.

As the hooks 5, 6 and 7 all engage the wire 9 above and below the horizontal center thereof, and as the hooks 5 and 6 are locked upon the wire 9 by the engagement of the hook 7 with the arm 8, the entire device is prevented from tilting, or its tilting is confined within very narrow and un- 110

objectionable limits, when the cable 10 is drawn therethrough in either direction.

I claim:—

1. A cable support comprising a cable receiving loop adapted to extend transversely beneath a supporting wire, a hook on one end portion of said loop and extending inwardly therefrom, an arm extending laterally from said hook, a hook on the other end portion of said loop and extending inwardly therefrom, said hooks facing different directions and being adapted to be passed upwardly on the respective sides of said wire to inclose said wire within said loop, said hooks being thereafter adapted to be hooked around said wire from opposite sides thereof, and the last named hook being adapted to extend between said arm and said wire to lock the first named hook upon said wire.

2. A cable support comprising a cable re-

ceiving loop adapted to extend transversely beneath a supporting wire, a pair of laterally spaced hooks one of which is connected to one end portion of said loops and both of which extend inwardly from said end portion, an arm connecting the hooks of said pair, a hook connected to the other end portion of said loop and extending inwardly therefrom, said pair of hooks and said hook facing different directions and being adapted to be moved past said wire on the respective sides thereof to inclose said wire within said loop, said pair of hooks and said hook being thereafter adapted to be hooked around said wire from opposite sides thereof, and the last named hook being adapted to extend between the hooks of said pair and between said arm and said wire to lock said pair of hooks upon said wire.

ORSON W. BRENIZER.
